PACK FOR STRETCH SOCKS

Orison W. Stone, Valley Cottage, N.Y., assignor, by
mesne assignments, to Riegel Paper Corporation, New
York, N.Y., a corporation of Delaware
Filed May 4, 1959, Ser. No. 810,755
3 Claims. (Cl. 206—46)

This invention relates to the art of packaging and more particularly to the packaging of socks, especially those of the type which are commonly referred to as "stretch socks."

This invention pertains, in one of its more specific aspects, to an improved insert unit comprising a novel insert element and at least one sock which tautly envelops the insert element. The invention also pertains to an improved holder unit for readily receiving, effectively retaining and advantageously displaying the socks of the insert unit.

The principal object of the invention is to provide a simple, attractive and inexpensive sock display pack having improved features of design and construction.

Another object of the invention is to provide an improved insert unit consisting of a relatively stiff insert element of novel design and a pair of socks which tautly envelop the insert element, such element being made from a one-piece blank of stiff foldable sheet material which is so configured as to avoid waste.

The invention has for another object the provision of a holder unit that is adapted to readily receive, retain and display and then permit of easy removal of an insert unit of the character indicated, the holder unit being made from a one-piece blank of a foldable sheet material which is so configured as to avoid waste.

A further object of the invention is to provide a sock display package which is simple and attractive in design, which is sturdy and durable in construction, which is reasonable in material and manufacturing costs and which has its parts so constructed and arranged as to permit of ready assembly.

The foregoing objects and additional objects, together with the advantages of the invention, will be apparent from the following detailed description taken in conjunction with the accompanying drawings which respectively describe and illustrate a preferred form of pack for displaying socks according to the invention.

In the drawings, wherein like reference characters denote corresponding parts throughout the several views:

FIG. 1 is a plan view of a blank from which a holder shown in other views is made;

FIG. 2 is a view in front elevation of a holder which is made from the blank of FIG. 1;

FIG. 3 is a view taken along line 3—3 of FIG. 2;

FIG. 4 is a plan view of a blank which serves as a sock insert element;

FIG. 5 is a plan view of an insert unit, prior to folding, and illustrates a pair of stretch socks mounted on and enveloping the insert unit of FIG. 4;

FIG. 6 is an enlarged plan view of the insert unit shown in FIG. 5 and illustrates the relative position of parts after folding;

FIG. 7 is a front elevation view of a completed pack consisting of the holder shown in FIG. 2 and the insert unit shown in FIG. 6, the insert unit having been turned 90° about its vertical axis; and

FIG. 8 is a plan view of the upper portion of a modified form of blank for use as a sock insert element.

Referring initially to FIG. 1, there is illustrated a blank B-1 which consists of a foldable sheet material such as a suitable weight and grade of an appropriate paperboard or a synthetic plastic composition. This blank is divided

2

by pluralities of fold lines and cut lines to define a back panel 10, a pair of side flaps 11, a top flap 12, a pair of top tabs 13, a bottom flap 14 and a pair of bottom tabs 15. The various flaps and tabs are adapted to be folded and glued, as will be described further along herein, to obtain the completed holder H which is shown in FIGS. 2 and 3.

Panel 10 is provided with a centrally located elongated through opening 16.

Each side flap 11 is hinged to panel 10 along a fold line 17 and is provided with a generally C-shaped outer edge notch 18. The lower end of each flap 11 is separated from panel 10 by an arcuate cut line 19.

Top flap 12 is hinged to the upper end of panel 10 along a fold line 20.

Each top tab 13 is hinged to a side of panel 10 along a fold line 21 which is a continuation of a corresponding fold line 17. Each of these tabs is separated from its adjacent side flap 11 by a cut line 22. This permits independent folding of individual flaps 11 and tabs 13 relative to panel 10.

Bottom flap 14 is hinged to the lower end of panel 10 along a fold line 23 which is parallel to fold line 20.

Each bottom tab 15 is hinged to a side of panel 10 along a fold line 24. It will be observed that fold lines 24 are spaced apart a greater distance than fold lines 17 and 21. As a result, the lower portion of panel 10 is wider than the remainder thereof.

Blank B-1 includes a pair of spaced and preferably identical areas 25 in its upper portion. Each of these areas has the general configuration of a diamond shaped parallelogram which is defined by lines of weakness, such as crease lines 26, 27, 28 and 29. Lines 26 are formed in panel 10 and extend downwardly and inwardly from the points of intersection of fold lines 20 and 21. Lines 27 are also formed in panel 10 and each extends upwardly and inwardly from a fold line 21 to the lower end of a corresponding crease line 26. Lines 28 are formed in side flaps 11. Each of these lines extends upwardly and outwardly from the lower end of a line 27 to a cut line 22. Lines 29 are formed in top tabs 13 and each extends from the upper end of a line 28 to the upper end of corresponding line 26.

In assembling holder H, side flaps 11 are first folded over panel 10 and secured thereto, preferably by gluing. It will be noted from an examination of FIGS. 2 and 3 that notched edged portions 18 of the panels align with portions of panel 10 which define opening 16 so that that opening is unobstructed in the completed holder. Top flap 12 and top tabs 13 are next folded over panel 10 to the relative position shown in FIGS. 2 and 3 and are glued together. Flap 12, tabs 13 and the upper portion of panel 10 define a top pocket P-1 which is open at its lower end. Bottom flap 14 and bottom tabs 15 are then folded over panel 10 to the relative position shown in FIGS. 2 and 3 and are glued together. Flap 14, tabs 15 and the lower portion of panel 10 define a bottom pocket P-2 which is open at its upper end.

Reference is next had to FIG. 4 which illustrates a sock insert blank B-2 which is made of a relatively stiff foldable sheet material, such as a suitable weight and grade of an appropriate paperboard. This blank consists of three principal parts, namely a top part 30, a leg part 31 and a foot part 32. The upper edge portions of top part 30 are generally sinusoidal in configuration, as indicated at 33, for reception and retention of the cuffs of a pair of socks. Leg part 31 has an elongated central opening 34 and is hinged to foot part 32 along a transverse fold line 35. The foot part is also provided with a central opening 36 that is identical with opening 34. When the

foot part is folded over the leg part along fold line 35, openings 34 and 36 will be in alignment.

Blank B-2 includes a pair of curved edge portions 37 which merge with top edge portions 33, a pair of parallel rectilinear edge portions 38, a first pair of inwardly curved edged portions 39 and a second pair of inwardly curved edge portions 40. As is shown in FIG. 4, corresponding edge portions 39 and 40 are symmetrical and intersect at fold line 35. The lower end of the blank is rounded, as indicated at 41, to define a toe portion at the free end of foot part 32.

Each of a pair of stretch socks S is adapted to be placed on and envelop the insert of FIG. 4, as illustrated in FIG. 5. Both socks are maintained taut longitudinally and transversely by the insert. Each sock has a top or cuff portion 42 which engages insert top part 30, a leg portion 43 which engages insert leg part 31, a foot portion 44 which engages insert foot part 32, a toe portion 45 which engages insert toe part 41 and a heel portion 46 which is located at the juncture of insert parts 31 and 32.

The sock and insert arrangement shown in FIG. 5 is adapted to be folded along line 35 so that the foot and toe portions of the socks and the corresponding parts of the insert overlie the leg and cuff portions as shown in FIG. 6. These parts, when so arranged, constitute an insert unit which is adapted to be disposed and retained in holder H, as illustrated in FIG. 7. In assembling the complete pack of FIG. 7, the lower portion of the insert unit shown in FIG. 6 is introduced into holder pocket P-2 and brought into registry with that pocket. This step in the procedure is facilitated by the tapered configuration of the lower portion of the unit of FIG. 6. The insert unit is then bowed and pocket P-1 is opened by finger pressure applied to weakened areas 25 of the holder. Simultaneous with the foregoing, the upper portion of the unit shown in FIG. 6 is introduced into the open end of pocket P-1 and urged upwardly into registry therewith. This completes assembly of the pack.

Opening 16 of the holder and openings 34 and 36 of the insert unit are of like size and configuration. Moreover, these openings are aligned in the complete pack (FIG. 7) and allow a prospective purchaser to feel the texture of the socks without dismantling the pack and removing the socks from the insert.

FIG. 8 illustrated the upper portion of a blank B-3 which may be used as the sock insert in lieu of blank B-2. Blank B-3 includes a top part 50 corresponding to top part 30 of blank B-2. Top part 50 is formed with corner notches 51 for receiving and retaining free end portions of a sock cuff. Also, the sides edges 52 of top part 50 are rectilinear instead of sinusoidal as in the case of edges 33 of blank B-2.

It will be apparent from the foregoing that the present invention affords a number of worthwhile benefits and advantages including the following.

(1) Blanks B-1, B-2 and B-3 from which the holder and the insert element are made, are economical in use of material;

(2) The die-cutting and gluing operations, in forming blank B-1 and assembling holder H therefrom, are simple and inexpensive and may be performed by the use of conventional equipment, thereby eliminating any need for costly special machinery;

(3) The reinforced construction embodied in the holder permits use of relatively lightweight boxboard;

(4) The provision of lines of weakness at the sides of holder top pocket P-1 allow that pocket to be opened by mere finger pressure at the time the insert unit is introduced into that pocket, thereby facilitating loading of the holder.

(5) The parts are so constructed and arranged as to permit rapid loading of the holder; and 6. By virtue of the fact that openings 16, 34 and 36 are in substantial alignment in the completed pack, a prospective purchaser

may conveniently feel the texture of the socks without disturbing any part of the pack.

From the foregoing, it is believed that the objects and advantages of my present invention will be readily recognized by persons trained in the art without further description. It is to be clearly understood, however, that various changes may be made in the sock pack described above without departing from the scope of the invention, it being intended that all matter contained in the description or shown in the drawings shall be interpreted as illustrative only and not in a limiting sense.

I claim:

1. In a holder for containing and displaying socks, said holder being made from a blank of a foldable sheet material comprising a panel, a top flap hinged to the upper end of the panel, a bottom flap hinged to the lower end of the panel and a pair of side flaps which are hinged to opposite sides of the panel, said side flaps overlying the front face of the panel and being secured thereto intermediate its sides, said top and bottom flaps overlying the front face of the panel, portions of the blank including the top flap and the upper part of the panel forming a top pocket which is open at its lower end, portions of the blank including the bottom flap and the lower part of the panel forming a bottom pocket which is open at its upper end, said pockets being spaced from each other and adapted to receive corresponding portions of a pair of socks, the upper portions of the panel and the side flaps being provided with intersecting lines of weakness to permit flexing of the parts which form the top pocket by finger pressure and thereby effect corresponding variations in the configuration of the open end of the top pocket, said panel and side flaps constituting a wall having a through opening which is wholly within its peripheral confines, said opening being at least partly defined by the portion of the wall which is intermediate the pockets.

2. In a holder for containing and displaying socks, said holder being made from a blank of a foldable sheet material comprising a panel, a top flap hinged to the upper end of the panel, a pair of top tabs which are hinged to opposite sides of the upper part of the panel, a bottom flap hinged to the lower end of the panel and a pair of bottom tabs which are hinged to opposite sides of the lower part of the panel, said flaps and tabs overlying the front face of the panel, said top flap and top tabs being joined together and forming, with the upper part of the panel, a top pocket which is open at its lower end, the top tabs and the panel being provided with lines of weakness adjacent each side of the holder to permit flexing of the parts which form the top pocket by finger pressure and thereby effect corresponding variations in the configuration of the open end of the top pocket, said bottom flap and bottom tabs being joined together and forming, with the lower part of the panel, a bottom pocket which is open at its upper end, said pockets being spaced from each other and adapted to receive corresponding portions of a pair of socks.

3. In a package for containing and displaying socks, a holder unit and a sock unit, said holder unit being made from a blank of a foldable sheet material comprising a panel, a top flap hinged to the upper end of the panel and a bottom flap hinged to the lower end of the panel, said flaps overlying the front face of the panel, upper portions of the blank including the top flap and the upper part of the panel forming a top pocket which is open at its lower end, said upper portions defining the top pocket provided with lines of weakness adjacent each side of the holder unit to permit flexing of the elements of the top pocket by finger pressure and thereby effect corresponding variations in the configuration of the open end of the top pocket, lower portions of the blank including the bottom flap and the lower part of the panel forming a bottom pocket which is open at its upper end, said pockets being spaced from each other, said

sock unit including an insert made from a blank of a stiff foldable sheet material comprising a top part, a leg part and a foot part, said top part being of reduced width, said leg part being disposed between the top and foot parts and being hinged to the foot part along a transverse fold line, and at least one sock stretched longitudinally and transversely on the insert with its foot portion enveloping the foot part, its leg portion enveloping the leg part and its cuff portion enveloping the top part, the insert and sock being folded along said fold line and constituting a folded insert unit which is mounted in the holder unit, one end of the folded insert unit registering with the top pocket and the other end registering with the bottom pocket.
